US00D968247S

(12) **United States Design Patent** (10) **Patent No.:** **US D968,247 S**
(45) **Date of Patent:** **** Nov. 1, 2022**

(54) **BANKNOTE COUNTING MACHINES**

(71) Applicant: **BILLCON CORPORATION**,
Kawasaki (JP)

(72) Inventor: **Yoshikazu Takagi**, Kawasaki (JP)

(73) Assignee: **BILLCON CORPORATION**,
Kawasaki (JP)

(**) Term: **15 Years**

(21) Appl. No.: **29/700,526**

(22) Filed: **Aug. 2, 2019**

(30) **Foreign Application Priority Data**

Mar. 14, 2019 (JP) 2019-005392

(57) **CLAIM**

The ornamental design for banknote counting machines, as
shown and described.

DESCRIPTION

FIG. 1 is a front perspective view of the banknote counting
machines;

FIG. 2 is a front elevational view of the banknote counting
machines;

FIG. 3 is a rear elevational view of the banknote counting
machines;

FIG. 4 is a top plan view of the banknote counting machines;

FIG. 5 is a bottom plan view of the banknote counting
machines;

FIG. 6 is a right side elevational view of the banknote
counting machines; and,

FIG. 7 is a left side elevational view of the banknote
counting machines.

The broken line showing of structural features is included
for the purpose of illustrating non-claimed subject matter
and forms no part of the claimed design.

1 Claim, 6 Drawing Sheets
